US0D1012962S

(12) **United States Design Patent** (10) **Patent No.:** **US D1,012,962 S**
(45) **Date of Patent:** **** Jan. 30, 2024**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Sumin Kim**, Suwon-si (KR); **Eunnim Cho**, Suwon-si (KR); **Younga Kim**, Suwon-si (KR); **Heuijin Kwon**, Suwon-si (KR)

(73) Assignee: **SAMSUNG ELECTRONICS CO., LTD.**, Suwon-si (KR)

(**) Term: **15 Years**

(21) Appl. No.: **29/828,397**

(22) Filed: **Feb. 25, 2022**

(30) **Foreign Application Priority Data**

Aug. 27, 2021 (CN) 202130563778.4

(51) **LOC (14) Cl.** **14-04**

(52) **U.S. Cl.**

USPC **D14/485**

(58) **Field of Classification Search**

(57) **CLAIM**

The ornamental design for a display screen or portion thereof with graphical user interface, as shown and described.

DESCRIPTION

The FIGURE is a front view of display screen or portion thereof with graphical user interface, showing our new design.

The outermost broken lines showing the display screen or portion thereof form no part of the claimed design. The remaining broken lines in the FIGURE depict portions of the graphical user interface that form no part of the claimed design.
